UNITED STATES PATENT OFFICE.

JAMES J. COLLINS, OF BOSTON, MASSACHUSETTS.

GUARD-RAIL FOR STREET-CARS.

SPECIFICATION forming part of Letters Patent No. 763,723, dated June 28, 1904.

Application filed November 9, 1903. Serial No. 180,816. (No model.)

To all whom it may concern:

Be it known that I, JAMES J. COLLINS, of Boston, county of Suffolk, State of Massachusetts, have invented an Improvement in 5 Guard-Rails for Street-Cars, of which the following description, in connection with the accompanying drawings, is a specification, like characters on the drawings representing like parts.

10 This invention relates to guard-rails for open street-cars, and has for its object to provide novel means for operating said guard-rails and for locking them in their out-of-use position.

15 Figure 1 shows in side elevation a street-car having a guard-rail embodying this invention. Fig. 2 is an enlarged detail of a portion of the guard-rail and means for operating it and the locking device. Fig. 3 is a vertical sectional detail of the guard-rail and means for operating it, showing the locking device in side elevation, the parts of the locking device being in the position they will occupy when the guard-rail is in its elevated or

20 out-of-use position. Fig. 4 is a vertical sectional detail showing the locking device with the parts in the position they will occupy when released preparatory to lowering the guard-rail when returning it to its lowermost position

25 Fig. 5 is a vertical sectional detail showing the locking device with the parts in the position they will occupy when the guard-rail is moving downward. Fig. 6 is a sectional detail showing a portion of the guard-rail and the guides for it. Fig. 7 is a detail showing a guard for the pinion which is mounted upon and secured to the guard-rail.

30 Fig. 8 is a detail showing a modified form of guide for the guard-rail. Fig. 9 represents the usual upright posts of the car, and b the usual handles or grab-bars. c is the guard-rail, which extends lengthwise of the car between the upright posts and the grab-bars, which are secured thereto, and is

35 adapted to be moved up and down between said posts and bars, which latter serve as guides. A hand-wheel c' is secured to each end of the guard-rail, by which said rail may be rotated. The rail has rigidly secured to it at or near each end and at as many other

points as desired along its length a pinion c², and the upright posts and also the grab-bars are grooved, as shown in Fig. 6, to form guides for the pinions, or specially-formed guides may be secured to said upright posts 55 and grab-bars, as shown in Fig. 8, to serve as guides for the pinions. At the bottom of the groove in the upright post a rack-bar c³ is secured, which is engaged by the pinion c², and the pinions are held in engagement with the 60 rack-bar by the guides. By turning the guard-rail on its axis it will be moved up and down, so as to occupy either its uppermost or lowermost position, as may be desired, and the operation may be very quickly accomplished. 65 When the guard-rail is in its lowermost position, it rests upon supports provided at the junction of the grab-bars and upright posts, and when said rail is in its uppermost position it is locked by a suitable locking device 70 provided for the purpose. One of the many forms of locking devices which may be employed for this purpose is herein shown for the sake of illustrating my invention; but I desire it to be understood that I do not limit 75 my invention to the particular form of locking device herein shown. The locking device herein shown comprises a latch d, pivoted at d' to the side walls of a shell d², which is set in a recess formed in the upright post a near 80 its upper end, or said locking device may be otherwise supported. A latch d normally projects from said shell into the path of movement of the guard-rail, so as to occupy a position beneath said guard-rail when the latter 85 is in its uppermost position, and thereby hold said rail in its uppermost position; yet said latch is free to be moved inward for the passage of the guard-rail. A spring d²⁰ is connected to said latch, the action of which is to 90 pull upon it in such manner as to normally hold its upper end projected outwardly into the path of movement of the guard-rail. Whenever the guard-rail is lifted, it engages the projecting end of the latch and passes by 95 as the latch yields, and then as the latch slips into position beneath the guard-rail it serves to obstruct the downward movement thereof. In Fig. 5 the latch is represented in the position it will occupy as the guard-rail moves 100

upward. To disengage the latch from the guard-rail, a releasing device is provided for said latch, which, as herein shown, comprises a bell-crank lever pivoted at e , one arm, as e' , of which projects into the path of movement of the guard-rail, and the other arm, as e'' , extends downward and is connected loosely with the latch by a link e^3 . The projecting arm e' or detent is lifted by the guard-rail by turning said guard-rail upward a short distance beyond its locked position, and when lifted the link e^3 will thrust the lower end portion of the latch d outward and will withdraw the upper end portion of the latch, and thereby permit the guard-rail to be lowered. In Fig. 4 the latch is shown as withdrawn to disengage the guard-rail. When the latch is withdrawn, it is necessary to lock it in its abnormal position until the guard-rail has descended below the engaging end of the latch, and to accomplish this result a spring-acting or yielding detent f is provided at the lower end of the shell d^2 when said latch is withdrawn from the path of movement of the guard-rail, said detent engaging and holding the latch d while the guard-rail descends below the engaging end of the latch. To disengage the latch from the detent, the lower end portion of the latch has a projection d^3 , which is formed with an inclined side adapted to be engaged by the guard-rail as the latter descends, and as the guard-rail passes by said projection the latch will be disengaged from the detent and restored to its normal position.

The pinions are guarded by curved plates i i' , located one above and the other below said pinion, said plates occupying positions between the upright posts and the grab-bars and held in place on the guard-rail by collars i^2 , which are loosely mounted on said rails. The uppermost guard i is preferably employed to operate the latch.

Having thus described my invention, what I claim as new, and desire to secure by Letters Patent, is—

1. A guard-rail for street-cars movable up and down between the upright posts and grab-bars, having pinions secured thereto, verti-

cally-supported rack-bars engaged by said pinions, means for turning the guard-rail, and a locking device for locking the guard-rail in its elevated position, substantially as described.

2. A guard-rail for street-cars movable up and down between the upright posts and grab-bars, having pinions secured thereto, vertically-supported rack-bars engaged by said pinions, means for turning the guard-rail, guards for said pinions, and a locking device for locking the guard-rail in its elevated position, substantially as described.

3. A guard-rail for street-cars movable up and down between the upright posts and grab-bars, having pinions secured thereto, vertically-supported rack-bars engaged by said pinions, means for turning the guard-rail, a locking device for locking the guard-rail in its elevated position, and means for releasing said locking device operated by the guard-rail, substantially as described.

4. A guard-rail for street-cars movable up and down between the upright posts and grab-bars, having pinions secured thereto, vertically-supported rack-bars engaged by said pinions, means for turning the guard-rail, a locking device for locking the guard-rail in its elevated position, and a shell containing said locking device, substantially as described.

5. A guard-rail for street-cars movable up and down between the upright posts and grab-bars, having pinions secured thereto, vertically-supported rack-bars engaged by said pinions, means for turning the guard-rail, a pivoted latch for locking the guard-rail in its elevated position, a releasing device for said latch, a locking device for said latch, and means for disengaging said latch from its locking device which is operated by the descending guard-rail, substantially as described.

In testimony whereof I have signed my name to this specification in the presence of two subscribing witnesses.

JAMES J. COLLINS.
